UNITED STATES PATENT OFFICE

EDWARD H. HAWES, OF NATICK, MASSACHUSETTS, ASSIGNOR TO H. HARWOOD & SONS, INC., OF NATICK, MASSACHUSETTS, A CORPORATION OF MASSACHUSETTS

DESIGN FOR A BALL

Application filed May 27, 1932. Serial No. 43,912. Term of patent 7 years.

To all whom it may concern:

Be it known that I, EDWARD H. HAWES, a citizen of the United States of America, residing at Natick, in the county of Middlesex and Commonwealth of Massachusetts, have invented a new, original, and ornamental Design for a Ball, of which the following is a specification, reference being had to the accompanying drawing, forming a part thereof.

The figure is a side view of a ball showing my new design.

The essential feature of my design consists

of a row of bosses or protuberances disposed in a curved or wavy line upon the surface of the ball, each boss or protuberance bordered or delimited by a polygonal stitch pattern.

I claim:

The ornamental design for a ball or similar article substantially as shown and described.

Signed by me at Natick, in the county of Middlesex and Commonwealth of Massachusetts, this 25th day of May, 1932.

EDWARD H. HAWES.
